UNITED STATES PATENT OFFICE.

ADOLPH RINIKER, OF LOS ANGELES, CALIFORNIA.

DESIGN FOR A SIGNAL-LAMP CASING.

Application filed October 18, 1927. Serial No. 23,783. Term of patent 7 years.

To all whom it may concern:

Be it known that I, ADOLPH RINIKER, a citizen of the United States, and resident of Los Angeles, California, have invented a new, original, and ornamental Design for a Signal-Lamp Casing, of which the following is a specification, reference being had to the accompanying drawing, forming part hereof.

I claim:

The ornamental design for a signal lamp casing, substantially as shown.

ADOLPH RINIKER.
